Primary Examiner — Austin Murphy(74) *Attorney, Agent, or Firm* — Neal, Gerber & Eisenberg LLP(57) **CLAIM**

The ornamental design for a strapping tool as shown and described.

DESCRIPTION

FIG. 1 is a perspective view of the strapping tool showing our new design;

FIG. 2 is a left-side view thereof;

FIG. 3 is a right-side view thereof;

FIG. 4 is a front elevational view thereof;

FIG. 5 is a back elevational view thereof;

FIG. 6 is a top plan view thereof; and,

FIG. 7 is a bottom plan view thereof.

The broken lines illustrate portions of the strapping tool that form no part of the claimed design.

1 Claim, 7 Drawing Sheets(56)
